UNITED STATES PATENT OFFICE.

PAUL MAUSER, OF OBERNDORF-ON-THE-NECKAR, GERMANY.

SMALL-ARM.

1,040,718.

Specification of Letters Patent.

Patented Oct. 8, 1912.

Application filed February 8, 1911. Serial No. 607,293.

To all whom it may concern:

Be it known that I, PAUL MAUSER, royal privy commercial councilor, a subject of the King of Wurttemberg, residing at 5 Oberndorf-on-the-Neckar, in the Kingdom of Wurttemberg, Germany, have invented certain new and useful Improvements in or Connected with Small-Arms, of which the following is a full, clear, and exact description.

This invention relates to an addition to or modification of the trigger-locking device protected by U. S. Patent No. 971,061, dated September 27, 1910, in which, for the 15 purpose of preventing the pulling of the trigger when the breech is unlocked, there is provided, within reach of the trigger device, a safety lever which is positively acted on by one or both of the locking levers, and 20 which, when these levers are in the unlocking position, is maintained by them in such position as to exert a locking action on the trigger parts.

Now, while in the construction described 25 in the specification of above mentioned patent the safety lever, like the locking levers, is arranged as a one arm lever moving inward and outward, in the construction to which this application relates there is adapted 30 a much simpler arrangement which dispenses with the safety lever above referred to, moving inward and outward with the locking levers, and substitutes for it a safety lever having the form of a two armed rocking lever which moves vertically and the front arm of which engages with a locking lever, while its rear arm engages with the trigger catch lever.

The accompanying drawings illustrate the 40 present improvement or addition to the construction to which the above mentioned patent relates, as applied to a recoil loader with fixed barrel of the Mauser system.

Figures 1 and 2 show the position of the 45 parts when the breech is properly locked and when the safety lever, and consequently also the trigger catch lever, are set free to permit of the pulling of the trigger. Figs. 3 and 4 illustrate the position of the safety 50 lever in the locking position with the breech unlocked whereby the safety lever, which is in the locking or safety position, engages the trigger catch lever and consequently prevents its downward movement when the 55 trigger is pulled, that is to say, it prevents the discharge of the weapon. Fig. 5 illus-

trates the coöperation of the trigger catch lever and the sear lever, the trigger catch lever being shown partially in section.

Referring to the general arrangement of 60 the breech, the locking levers are, in this case, arranged, as heretofore, as a pair of levers *b*, *b*, which support the breech-block from the rear, and are pivotally mounted in the rear wall of the breech casing, and 65 which, when turned inward are in the locking position and turned outward are in the unlocking position, the levers in the former position exerting a locking action on the breech block and in the latter position permitting of its movement to the rear between the locking levers. Beneath the left locking lever *b* there is pivotally mounted on the central web or fillet *g*¹ of the stock *g* the two armed safety lever *p*, which latter is 70 provided on its front arm *p*¹ with an upwardly projecting nib *p*⁰ which, when the locking lever *b* is in the locking position, engages with a corresponding recess *b*⁰ there- 75 in. The rear arm *p*² of the safety lever terminates in a projection or catch *p*³, above which engages the hook shaped end *z*³ of the trigger catch lever *z*². This hook shaped end *z*³, however, not only engages above the projection or catch *p*³ of the arm *p*² of the 80 safety lever, but at the same time also over the hook *s*³ of the sear lever *s*² which is rotatably mounted in the usual manner on the pin *s*¹ from the lower projection of the lock *g* and which engages with the firing pin by 85 means of the sear *s*.

When the mechanism is properly locked, that is to say, when, as already stated, the nib *p*⁰ of the safety lever engages with the recess *b*⁰ of the locking lever *b*, the trigger 95 can be drawn back without obstruction, as in consequence of the fact that the safety lever can perform its oscillatory movement, the sear lever can be swung downward by the trigger catch lever and can consequently 100 release the firing pin. If, on the contrary, the locking has not been effected so that the locking lever is turned outward, the nib *p*⁰ will be unable to enter the recess *b*⁰, with the result that the safety lever will be held 105 fast in the position shown in Fig. 3 and that the trigger cannot move the arm *p*², together with the trigger catch lever *z*², downward, but such parts will be so held as to be incapable of downward movement, the pulling 110 of the trigger and the consequent release of the firing pin thus becoming impossible.

The trigger catch lever z^2 , which is pivotally attached to the trigger z , and is furnished toward its rear with a sliding catch y , is furnished at its lower end with a striking arm z^1 which is formed by a prolongation extending beyond the fulcrum.

When, upon the discharge of the weapon, the release of the firing pin having been effected, the trigger is drawn farther toward the rear, the lower stepped end of the arm z^1 comes in contact with a stop u^1 provided at the upper side of the trigger guard u and thus brings about the disengagement of the hook z^3 from the hook s^3 of the sear lever s^2 , with the result that even should the trigger not be released, the sear lever, being set free from the trigger catch lever, can return into the engaging position ready for the next shot. By this means it is insured that the trigger mechanism will act properly at each shot so that when, after the shot, the trigger has been drawn back, the firing parts are caught independently of the trigger mechanism. To effect a fresh discharge it is sufficient to release the trigger, when the catch lever will at once assume its engaging position in relation both to the sear lever and to the safety lever.

What I claim as my invention and desire to secure by Letters Patent is:

1. In a breech-loading fire-arm, the combination with a breech bolt, of locking levers therefor, firing mechanism comprising a trigger, means engaged by said trigger adapted to lock said trigger when said locking levers are in unlocking position, and means adapted to disengage said trigger and locking means when said trigger is pulled to release the firing mechanism.

40 2. In a breech-loading fire-arm, the combination with a breech bolt, of locking levers therefor, firing mechanism comprising a trigger, and a lever adapted to be engaged by said trigger and directly coöperating with said locking levers to lock said trigger against operation when said locking levers are in position to unlock the breech.

3. In a breech-loading fire-arm, the combination with a breech bolt, of locking levers therefor, firing mechanism comprising a trigger, a lever adapted to be engaged by said trigger and coöperating with said locking levers to lock said trigger against operation when said locking levers are in position to unlock the breech, and means adapted to disengage said trigger and lever when the trigger is pulled to release the firing mechanism.

4. In a breech-loading fire-arm, the combination with a breech bolt, of locking levers therefor, firing mechanism comprising a trigger and a sear, a lever adapted to be engaged by said trigger, and coöperating with said locking levers to lock said trigger against operation when said locking levers

are in position to unlock the breech, and means adapted to disengage said trigger and lever immediately after with the disengagement of said trigger and sear.

5. In a breech-loading fire-arm, the combination with a breech bolt, of locking levers therefor, firing mechanism comprising a trigger, and a two-arm rocking lever adapted to be engaged at one end by said trigger and at its other end directly coöperating with said locking levers to lock said trigger against operation.

6. In a breech-loading fire-arm, the combination with a breech bolt, of locking levers therefor, firing mechanism comprising a trigger, a two-arm rocking lever adapted to be engaged at one end by said trigger and at its other end coöperating with said locking levers to lock said trigger against operation, and means automatically disengaging said two-arm lever and trigger upon movement of said trigger after release of said firing mechanism to fire the gun.

7. In a breech-loading fire-arm, the combination with a breech bolt, of locking levers therefor, firing mechanism comprising a trigger and a catch pivoted thereto, and a two-arm rocking lever adapted to be engaged at one end by the catch of said trigger and at its other end coöperating with said locking levers to lock said trigger against operation.

8. In a breech-loading fire-arm, the combination with a breech bolt, of locking levers therefor, firing mechanism comprising a trigger and a catch pivoted thereto intermediate its ends, and a two-arm rocking lever adapted to be engaged at one end by the catch of said trigger and at its other end coöperating with said locking levers to lock said trigger against operation, and a stop adapted to engage an end of said catch to disengage the catch and two-arm lever upon movement of said trigger after release of said firing mechanism to fire the gun.

9. In a breech loading firearm, the combination with a breech bolt, of locking-levers therefor, a safety lever in position to be locked by a locking-lever when the locking-levers are in unlocking position, and a firing mechanism comprising a trigger normally in engagement with said safety lever, said lever retaining said trigger in engagement therewith while the locking-levers are in unlocking position and disengaging therefrom when the trigger is pulled with said locking-levers in locking position.

10. In a breech loading firearm, the combination with a breech bolt, of locking-levers therefor, a vertically oscillating safety lever in position to be locked by a locking-lever when the locking-levers are in unlocking position, and a firing mechanism comprising a trigger normally in engagement with said safety lever, said lever retaining said

trigger in engagement therewith while the locking-levers are in unlocking position and disengaging therefrom when the trigger is pulled with the locking-levers in locking position.

11. In a breech-loading firearm, the combination with a breech-bolt, of locking-levers therefor, a safety-lever in position to be locked by a locking-lever when the locking-levers are in unlocking position, and a firing mechanism comprising a sear, a trigger, and a catch upon said trigger normally engaging both said sear and safety lever, said lever retaining said catch in engagement

therewith and with said sear while said locking-levers are in unlocking position, said catch being adapted to disengage therefrom and from said sear when the trigger is pulled and said locking-levers are in locking position.

In witness whereof, I have hereunto signed my name in the presence of two subscribing witnesses.

PAUL MAUSER.
